UNITED STATES PATENT OFFICE

147,437

DESIGN FOR A MOTOR ANALYZER CABINET

Irvin W. Folk, Belleville, N. J., assignor to Atlas Supply Company, Newark, N. J., a corporation of Delaware

Application February 4, 1946, Serial No. 126,239

Term of patent 14 years

(Cl. D26—5)

To all whom it may concern:

Be it known that I, Irvin W. Folk, a citizen of the United States, residing at Belleville, in the county of Essex and State of New Jersey, have invented a new, original, and ornamental Design for a Motor Analyzer Cabinet, of which the following is a specification, reference being had to the accompanying drawing, forming a part thereof.

Referring to the drawing:

Fig. 1 is a perspective view of a motor analyzer cabinet, showing my new design; and

Fig. 2 is a side elevational view thereof.

I claim:

The ornamental design for a motor analyzer cabinet, as shown.

IRVIN W. FOLK.
